UNITED STATES PATENT OFFICE.

CHARLES PFANSCHMIDT, OF CHICAGO, ILLINOIS, ASSIGNOR TO THEO. A. KOCHS COMPANY, OF CHICAGO, ILLINOIS, A CORPORATION OF ILLINOIS.

DESIGN FOR A BARBER-SHOP MIRROR.

No. 39,853.

Specification for Design.

Patented March 2, 1909.

Application filed September 15, 1908. Serial No. 453,211. Term of patent 7 years.

To all whom it may concern:

Be it known that I, CHARLES PFANSCHMIDT, a citizen of the United States, residing at Chicago, in the county of Cook and State of Illinois, have invented a new, original, and ornamental Design for a Barber-Shop Mirror, of which the following is a specification, reference being had to the accompanying drawing, forming a part thereof.

The figure is a perspective view of a barber shop mirror showing my new design.

I claim:—

The ornamental design for a barber shop mirror, as shown.

CHARLES PFANSCHMIDT.
